by Quig & Lane at his

UNITED STATES PATENT OFFICE.

NORTON B. HASKINS, OF ADEL, IOWA.

BOTTLE-RETAINING DEVICE FOR ICE-BOXES.

No. 894,736.

Specification of Letters Patent.

Patented July 28, 1908.

Application filed June 24, 1905. Serial No. 266,874.

To all whom it may concern:

Be it known that I, NORTON B. HASKINS, a citizen of the United States, residing at Adel, in the county of Dallas and State of Iowa, have invented a certain new and useful Bottle-Retaining Device for Ice-Boxes, of which the following is a specification.

The objects of my invention are to provide a device for holding bottles in a refrigerator in position where they are easily accessible and from which the lowermost bottle is in such position that it can be easily removed from beneath the other bottles which are above it, and to also provide such a device so that the supply may be always kept fresh by withdrawing the bottle which is put into the receptacle first.

A further object is to provide a device of this class in which the lowermost bottles will be kept colder than the other bottles, and hence will be in readiness for use before the bottles above.

A further object is to provide a mechanism for supporting the bottles nearest the lowermost bottles at their free ends while these lowermost bottles are being removed.

A further object is to provide a device of this class which can be easily placed in any of the ordinary refrigerators and which can be easily removed therefrom, and further to provide a protector which will cause the water dropping from the ice in the top of the refrigerator to be carried to a point above the rear of the bottles and prevent it from dropping onto the labels.

A further object is to provide compartments to receive bottles containing various substances, so that these substances can be separated from each other, and the necessity of separating these bottles from each other, every time a bottle has to be removed, is obviated.

My invention consists in certain details in the construction, arrangement and combination of the various parts of the device, whereby the objects contemplated are attained, as hereinafter more fully set forth, pointed out in my claims and illustrated in the accompanying drawings, in which:

Figure 1 is a front elevation of my device in position in a refrigerator. Fig. 2 is a vertical, sectional view of my device and the refrigerator. Fig. 3 is a perspective view of my device, and Fig. 4 is a detail view of the spring for maintaining the bottles in the various compartments in position.

Referring to the accompanying drawings, it will be seen that there is provided an ordinary ice box having an upper compartment 10 and a lower compartment 11 which are separated from each other by a perforate ice supporting member 12, at the front of which there is a door 13. In the front portion of the lower compartment there is a door made in two parts 14 and 15 which are hinged to the front of the ice box and beneath the door 13. Extending across the ice box beneath the support 12 is a slide drip pan 16 which is inclined from the front of the ice box downwardly as it approaches the rear portion, and an opening is provided between the rear edge of the drip pan 16 and the forward side of the back portion of the ice box to provide an opening 18 through which the water dripping from the ice in the upper compartment will be allowed to fall onto this drip pan and will flow rearwardly on the pan through the opening 18 into the lower compartment.

Designed to be mounted in the lower compartment 19 of the ice box is a bottle case 80 which is divided into a series of compartments 20, 21, 22 and 23 which may be made of any desirable material and in which there may be any desirable number of compartments, provided these compartments are of sufficient width and depth to permit the bottles being received in them. These compartments are formed by a back portion 24 which has the extensions 25 and 26 at its ends, which extensions 25 and 26 are at substantially right angles to the back portion 24 and parallel with each other, as shown clearly in Fig. 3. Spaced apart between the extensions 25 and 26 I have provided the partitions 27, 28 and 29 to form the compartments 20, 21, 22 and 23. The portions of the extensions 25 and 26 are secured together by the connecting piece 30 which is also connected to the partitions 27, 28 and 29. Attached to the connecting piece 30 and in front of each of the various compartments 20, 21, 22, and 23 is a card holder 31 in which cards are designed to be placed to indicate the substance contained in the bottles in the various compartments. Attached to the front edge of the extension 25 is a retaining member 32 which is curved at its upper and lower ends. Attached to the front edge of the extension 26 is a retaining member 33 similar in construction to the retaining member 32. Both of these retaining members 32 and 33 extend from the part to which they

are attached inwardly toward each other a slight distance, so as to project over the compartments 20 and 23 respectively a slight distance. Secured to the front edge of the 5 partition 31 is a retaining member 34 which projects at each side of the partition to which it is attached, and into the compartments 20 and 21. Attached to the front edge of the partition 28 is a retaining member 35 which 10 projects into the compartments 21 and 22 and beyond each side of the partition 28. Attached to the front edge of the partition 27 is the retaining member 36, which extends at each side of the parts to which it is attached and into the compartments 22 and 15 23. Each of these retaining members 34, 35 and 36 are rounded at their upper and lower ends, as shown clearly in Fig. 3 of the drawings.

20 Pivots attached to the lower portion of the retaining device 34 are two supporting members 37 and 38 which are maintained at their upper limit of movement by means of the spring 39. Pivots attached to the 25 front lower portion of the retaining member 36 are the supports 40 and 41 which are supported at their upper limit of movement by means of a spring 42 similar in construction to the spring 39. These supports 40 and 41 30 may be made of any desirable material and in any way that is found convenient for supporting the outer ends of the bottles when they are placed in the various compartments 20, 21, 22 and 23.

35 When it is desirable to place the bottles, say of one kind of substance, such as vanilla soda water, and assuming that the compartment 20 was to be used for this purpose, the bottles which would be slipped into this 40 compartment would be taken one at a time and moved into the compartment 20 above the retaining members 32 and 34 and allowed to move downwardly until the neck of the bottle rested against the support 37 and the 45 remaining bottles would be placed in the compartment until it was filled. When it is desirable to remove one of the bottles, the neck of it is moved downwardly against the resistance of the spring 39 which maintains 50 the neck of the bottles above the bottom of the compartment until the neck of this bottle is beneath the support 38 at which time the bottle immediately above the one thus moved downwardly will be engaged by the 55 support 38 and will be maintained in position while the lowermost bottle is withdrawn from the compartment. This operation is easily repeated and the lowermost bottle easily withdrawn because of this arrangement.

60 In the bottom of the lower compartment of the ice box, and beneath the compartments 20, 21, 22 and 23 I have provided a small tank 43 in which the lowermost bottle in each of the various compartments normally stands.

This tank is to receive the cool water from the ice as it drips from the edge of the drip pan 16 through the opening 18, and to cool the lowermost bottle more rapidly and to keep it cool constantly while the device is 70 being used. Then too, the bottles are all kept much cooler on account of the water passing over these bottles from the cake of ice in the upper compartment 10 to the tank 75 43. I have provided an outlet pipe 44 from this tank 43 to prevent any overflow of the tank except through this outlet pipe where it can be easily taken care of.

By the use of this device, the lowermost bottle; that is, the one which is lowest in the 80 various compartments 20, 21, 22 and 23 will be removed before those which are above it, and thus the coldest will be sold first. It is also my purpose to provide a bottle case for 85 ice boxes which can be made of any desirable size and which may have compartments of various sizes, and which can be easily placed in or removed from the ordinary ice box or refrigerator.

Having thus described my invention, what 90 I claim and desire to secure by Letters Patent of the United States, therefor is—

1. A case for bottles, comprising a series of vertical compartments designed to receive bottles, one above the other in each compartment, means for retaining bottles in each compartment, means for supporting the necks of all bottles above the lowermost while the lowermost one is being removed, and a card holder at the upper portion of each compartment for identifying the contents of the bottles in the compartments. 100

2. A case for bottles, comprising a series of vertical compartments designed to receive bottles, one above the other in each compartment, means for retaining bottles in each compartment, spring maintained means for supporting the necks of all bottles above the lowermost while the lowermost is being removed, and card holders at the upper portion 105 of each compartment for identifying the contents of the bottles in the compartments. 110

3. In an ice box, an upper and lower compartment, a bottle case detachably mounted in the lower compartment, and a drip pan 115 mounted between the upper and lower compartments with an opening between it and the rear portion of the lower compartment.

4. In an ice box, an upper and lower compartment, a bottle case in the lower compartment, comprising a series of compartments, means for retaining the bottles in each compartment, so arranged that the bottles may be inserted into each compartment above the retaining means and withdrawn from it beneath the retaining means and the necks of the bottles will extend outside of the compartment. 120

5. In an ice box, an upper and lower compartment, a bottle case in the lower compartment, 125

ment, comprising a series of compartments, means for retaining the bottles in each compartment, so arranged that the bottles may be inserted into each compartment above the 5 retaining means and withdrawn from it beneath the retaining means and the necks of the bottles will extend outside of the com-

partment, and means for supporting the necks of the bottles above the bottom of the compartments.

NORTON B. HASKINS.
